INSTRUMENT FOR INSERTING CORNEAL LENSES

Charles Batka, 592 Prospect Ave.,
West Orange, N.J. 07052

Filed May 26, 1967, Ser. No. 7,279

Term of patent 14 years

(Cl. D57—1)

FIG. 1

FIG. 3

FIG. 2

FIG. 4

FIG. 1 is a perspective view of an instrument for inserting corneal lenses showing my new design;

FIG. 2 is a top plan view thereof;

FIG. 3 is a side elevation thereof, the opposite side is a mirror image on the side shown; and

FIG. 4 is a bottom plan view thereof.

The electric plug and cord element are shown in broken lines for illustrative purposes only.

I claim:

The ornamental design for an instrument for inserting corneal lenses, as shown and described.
